OFF GAS FIRING SYSTEM

Peter von Wiesenthal, New York, N.Y., assignor to Alcorn Combustion Company, New York, N.Y., a corporation of Delaware

Filed June 12, 1964, Ser. No. 374,686

4 Claims. (Cl. 158—7)

This disclosure relates to firing carbon monoxide in lean concentrations occurring in exhaust from hydrocarbon catalytic cracking units. The invention contemplates a stack and seal pot arrangement especially suited to this service.

Commercial CO-firing systems must provide not only for the condition of firing but also for the condition when the CO-firing unit is out of service for maintenance. In the former condition off gas is fed to the CO-firing unit, and combustion products are vented to the atmosphere via a stack. The latter condition calls for bypassing the CO-firing unit by delivering the off gas directly to the stack. The present advance accommodates both of these conditions in a particularly facile manner by integrating seal pot construction with fabrication of the stack. More particularly, a stack is fashioned with an inner flue as well as an outer flue mounted about the inner flue. During normal operation products of combustion are exhausted to the atmosphere via the outer flue. When the CO-firing unit is out of service and off gas is to be bypassed around the CO-firing unit, the off gas is vented via the inner flue. A seal pot mounted in the stack controls flow of the bypass off gas to the inner flue.

Basically, the arrangement here advanced offers increased safety, economy and ruggedness over comparable systems. Mounting of the bypass seal pot in the stack gives an added measure of safety in the event of CO leakage. CO-firing systems are characterized by high temperatures and velocities as well as wide savings in operating conditions. Seal pots receive especially sore abuse. Here the bypass seal pot is integrated into the formidable structure of the stack. Compatibility of the stack structure with that of the bypass seal pot gives rise to savings. Further, the inner annulus stiffens the stack for greater resistance to wind loads and vibrations.

These and other features will appear more fully from the accompanying drawing wherein:

FIGURE I is a diagrammatic illustration of the off-gas firing system here contemplated.

FIGURE II is an enlarged elevation in section of the lower portion of the stack.

The off gas firing arrangement set forth herein provides for either CO-firing unit 1 being in service or out of service. As best seen in FIGURE I during normal operation feed seal pot 2 can be opened and bypass seal pot 3 can be closed so that off gas from catalyst regenerator 4 would be fed via feed duct 6 to CO-firing unit 1 where it is burned in a manner well known to petroleum refiners. Usually air and auxiliary fuel are added to the burning off gas. Heat is recovered from the products of combustion by means of non-contact heat exchange with a process stream in tube coil 7. Products of combustion exit CO-firing unit 1 by way of exhaust duct 8. These combustion products pass through exhaust port 9 and are vented through outer flue 11 and outer top opening 12 of stack 13.

When CO-firing unit 1 is not in service, feed seal pot 2 would be closed to prevent off gas from entering CO-firing unit 1 through feed duct 6. Bypass seal pot 3 would be opened so that off gas is shunted to the atmosphere by way of inner flue 14 and inner top opening 16.

Bypass seal pot 3 is formed integrally with stack 13.

2

Pot 17 with bottom 18 and peripheral shell 19 is connected in sealing engagement about lower end 21 of inner annulus 22. Lower end 21 projects downward into interior 23 of pot 17 and is spaced from shell 19 so that bypass chamber 24 is defined between inner annulus 22 and shell 19. Bypass duct 26 connects feed duct 6 upstream of feed seal pot 2 with bypass chamber 24 above lower end 21 of inner annulus 22 from whence, when CO-firing unit 1 is not in service, the off gas can pass under lower end 21 through inner flue 14 and out inner top opening 16.

Bypass seal pot 3 is operated by pool of water 27 so that when the level 28 of the water is above lower end 21 a head of water can be maintained across the lower end 21 of inner annulus 22.

Off gas is generally exhausted from catalyst regenerators at temperatures from 800° to 1100° F. Further, carbon monoxide which comprises from 3 to 10% of the off gas is quite lethal. So when CO-firing unit 1 is to be entered for repair work, it is necessary that both feed duct 6 and exhaust duct 8 be positively closed. Positive closure is accomplished by means of feed 29 and exhaust 31 guillotine dampers. Feed seal pot 2 must usually be closed in order for feed guillotine damper 29 to be moved into its closed position.

It will be apparent to those skilled in CO firing that wide deviations can be made in the details of this disclosure without departing from the main theme of invention as set forth in the claims.

What is claimed is:

1. A system for firing off gas from the catalyst regenerator of a hydrocarbon catalytic cracking unit and comprising in combination

a feed duct which connects in flow series with the catalyst regenerator to receive off gas therefrom, a CO-firing unit,

the feed duct connected in flow series with the CO-firing unit to deliver the off gas thereto, means operatively associated with the CO-firing unit for recovering heat from combustion products generated therein,

a feed seal means operatively connected in the feed duct for controlling the supply of off gas to the CO-firing unit,

a stack with an inner annulus and an outer annulus, the inner annulus defining an inner flue, the outer annulus spaced from the inner annulus to define an outer flue therebetween, both of the annuli describing top openings so that the inner and outer flues vent to the atmosphere, means for exhausting combustion products from the

CO-firing unit via the outer flue, a bypass duct connecting the feed duct upstream of the feed seal means in flow series with the inner flue, bypass seal means mounted internally of the outer annulus and operatively associated with the bypass duct for controlling the flow of off gas to the inner annulus.

2. A system for firing off gas from the catalyst regenerator of a hydrocarbon catalytic cracking unit and comprising in combination

a feed duct which connects in flow series with the catalyst regenerator to receive off gas therefrom, a CO-firing unit,

the feed duct connected in flow series with the CO-firing unit to deliver the off gas thereto, means operatively associated with the CO-firing unit for recovering heat from combustion products generated therein,

a feed duct connected in flow series with the CO-firing unit to deliver the off gas thereto,

means operatively associated with the CO-firing unit for recovering heat from combustion products generated therein,
 a feed seal means operatively connected in the feed duct for controlling the supply of off gas to the CO-firing unit,
 a stack with an inner annulus and an outer annulus, the inner annulus defining an inner flue,
 the outer annulus spaced from the inner annulus to define an outer flue therebetween,
 both of the annuli describing top openings so that the inner and outer flues vent to the atmosphere,
 the outer annulus of the stack defining an exhaust port, an exhaust duct connecting the CO-firing unit to the outer annulus of the stack about the exhaust port for exhausting combustion products to the outer flue,
 a bypass seal pot with a bottom and a peripheral shell connected in sealing engagement about the lower end of the inner annulus,
 the lower end of the inner annulus projecting downward into the interior of the bypass seal pot and spaced from the shell so that a bypass chamber is defined between the inner annulus and the shell,
 a bypass duct connecting the feed duct upstream of the feed seal means with the bypass chamber above

5

 15

the lower end of the inner annulus from whence when the CO-firing unit is not in service the off gas can pass under the lower end of the inner annulus to the inner flue,
 means for introducing a pool of water into the bypass seal pot whereby when the level of the water is above the lower end of the inner annulus a head of water can be maintained across the inner annulus.
 3. The system of claim 2 with
 means operatively connected to the feed duct downstream of the bypass duct for positive closure of the feed duct,
 and means operatively connected to the exhaust duct for positive closure thereof.
 4. The system of claim 3 with guillotine dampers providing for positive closure of the feed duct as well as the exhaust duct.
